(57) **CLAIM**

The ornamental design for a fidget device for sensory therapy, as shown and described.

DESCRIPTION

FIG. 1 is a front perspective view of a fidget device for sensory therapy showing our new design;

FIG. 2 is a front view of the fidget device for sensory therapy of FIG. 1;

FIG. 3 is a rear view of the fidget device for sensory therapy of FIG. 1;

FIG. 4 is a left side view of the fidget device for sensory therapy of FIG. 1;

FIG. 5 is a right side view of the fidget device for sensory therapy of FIG. 1;

FIG. 6 is a top view of the fidget device for sensory therapy of FIG. 1; and,

FIG. 7 is a bottom view of the fidget device for sensory therapy of FIG. 1.

The broken lines in the drawings show portions of the fidget device for sensory therapy that form no part of the claimed design.

1 Claim, 5 Drawing Sheets
